BUILDING

Karl F. Otto, Brookline, Pa.

Application January 8, 1936, Serial No. 58,205

7 Claims.

(Cl. 20—1)

This invention relates to new and useful improvements in building construction and more particularly to the construction of buildings of the so-called pre-fabricated unit or sectional type.

The principal object of the present invention is to provide certain improvements in unit or sectional building construction wherein buildings may be readily assembled where desired with the use of relatively few different forms of sections, units or the like.

Another object of the invention is to provide a standard or basic unit or section for use in the construction of buildings of the present character which is of simple durable construction and relatively inexpensive to manufacture, because effective use may be made of "run of the tree" and short length unmarketable building stock as well as synthetic sheathing, lining products and otherwise wise waste material.

Another object of the invention is to provide a sectional building construction wherein the component sectional units may be relatively interlocked with one another to effect a substantially more rigid structure than heretofore.

Another object of the invention is to provide a standard or basic unit or section for use in the construction of buildings which is pre-fabricated and factory finished including doors and windows completely fitted, hung and glazed and provided with necessary hardware to permit relatively rapid field assembly and completion for early occupancy.

A further object of the invention is to provide a sectional building of the character set forth which does not require the services of skilled labor to assemble and may therefore be erected at a minimum cost.

A further object of the invention is to provide a sectional building of the stated character which may be erected in various floor plans and sizes and which when assembled may be added to from time to time in accordance with the desires and needs of the owner, as regards room sizes and increased accommodations as well as the application of further decorative and useful embellishments thereto.

A still further object of the invention is to provide certain companion sections or units such as flooring, ceiling, roofing and the like for use with standard or basic sections in the erection of a building.

Other objects of the invention and the features and details of construction thereof are set forth

hereinafter, and shown in the accompanying drawings, in which:

Fig. 1 is a view in perspective of a standard or basic building unit or section made in accordance with the present invention.

Fig. 2 is a view in section on line 2—2, Fig. 1.

Fig. 3 is a view in section on line 3—3, Fig. 1.

Fig. 4 is a view in section similar to Fig. 3 showing another or modified form of section or unit.

Fig. 5 is an enlarged fragmentary view in section horizontally through a portion of a wall showing a window or door unit incorporated therein.

Fig. 6 is a fragmentary view in section vertically through a one-story building embodying the invention.

Fig. 7 is a fragmentary view in section on line 7—7, Fig. 6.

Fig. 8 is a fragmentary view in section vertically through a building showing the adaptation of the invention to a building having more than one floor or story; and

Fig. 9 is a fragmentary view in section on line 9—9, Fig. 6.

Referring now to the drawings, reference numeral 1 designates generally a pre-fabricated structural section or unit made in accordance with the present invention and used extensively as wall and partition members in the assembly or erection of a building. As shown in Figs. 1, 2 and 3 of the drawings, the units or sections 1 comprise a frame or skeleton of rugged construction including top and bottom end members 2 and 3, upright or vertical side members 4 and 5 and cross members or struts 6 extending horizontally between said vertical side members 4 and 5 in substantially equally spaced relation with respect to each other and said top and bottom end members 2 and 3, in interior partition units and at sill and head levels respectively in exterior wall units so that windows and doors may be located therein at the option and desire of the owner.

As shown, the opposite side faces of the frame or skeleton are respectively surfaced or covered with sections or panels of ply-wood or other weather impervious material 7 and sections or panels of insulating material 8 such as fibre board, sheet rock or the like, the ply-wood or like material 7 being used in instances where that side of the unit or section 1 faces externally of a building and is exposed to the elements of nature. It will be observed from the drawings that the surfacing panels or sections 7 and 8 completely enclose the spaces intermediate the component

elements of the frame or skeleton to provide a plurality of dead air spaces 9, 10 and 11 in each unit or section 1 which function in cooperation with the insulating panel 8 to prevent the radiation of heat in either direction through said units or sections.

The wall and partition sections or units 1 are constructed and arranged for relatively interlocking engagement along their marginal edges 10 with adjacent sections 1 as well as certain companion units to be described hereinafter, and this is accomplished in the present instance by providing surface panels 7 and 8 of substantially equal size and securing the same to the opposite 15 faces of the frame or skeleton in predetermined relation with respect to the edges of the latter so that said panels project an equal distance beyond both top and bottom end members 2 and 3 and one intermediate vertical side member 5 thereof 20 to form marginal grooves 12, 13, and 14 respectively, and the other vertical side member 4 of the frame or skeleton projects outwardly beyond the adjacent side edges of the panels a distance somewhat less than that which said panels project 25 beyond the skeleton structure at the other edges thereof to provide a projecting vertically disposed tongue 15, the cross sectional dimensions and shape of which are otherwise substantially the same as the corresponding cross sectional dimensions 30 and shape of each of the marginal grooves 12, 13 and 14 previously described. By constructing the wall and partition units 1 in the foregoing manner it will be observed that the projecting tongue element 15 will snugly engage the groove 35 13 of adjacent units to effectively interlock the same along the line of abutment thereof, and by constructing said tongue 15 so that the same projects a less distance beyond the panels 7 and 8 than the depth of said groove 13, a neat and tight 40 juncture or fit-up of the adjacent side edges of the sheathing or panels 7 and 8 of said abutting interlocked units or sections is effected. Similar wall and partition units designated generally as 1a and employed at corners in the walls and partitions of 45 a building are disposed substantially at right-angles as shown in Fig. 7 of the drawings, and constructed substantially the same as the wall and partition units 1, differing therefrom in that the abutting vertical side elements 4a of the frames or skeletons thereof are provided with complementary mitered edge portions 16 and rabbeted offsets 50 so that the same will snugly interlock with the panels or facings of adjacent corner sections in proper alignment with one another.

Door and window wall and partition units 1b are also constructed substantially identical to the units 1 except that door and window frames 17 are substituted for the panels 7 and 8 and marginal grooves are provided at both side and end edges 60 thereof, eliminating the projecting tongue construction at one side edge of the standard or basic units as well as the problem of determining proper right and left hand construction of such door and window units for any particular building layout.

In the event that the arrangement of walls and partitions in a building is such that one side edge groove of a unit is positioned adjacent one side edge groove of another wall or partition unit, as 65 shown in Figs. 5 and 7 of the drawings, said units 70 may be locked together by means of an independent key or feather 18 inserted into engagement with both of the grooves in said abutting units. In addition, gable, wall and partition units 1c are also provided and these are of substantially the 75 same construction as the wall and partition units

1, but differ therefrom in that the same are constructed and arranged so that the marginal groove 12a at the top end thereof is disposed at an angle corresponding to the angle of inclination of the roof of the particular building as illustrated in 5 Fig. 6 of the drawings.

Prior to the erection of a building embodying the present invention, a suitable foundation structure 19 is provided and supports a plurality of pre-formed floor units designated generally as 20 including a frame having side and end beams or the like 21 and 22 respectively, and smaller cross beams, struts or the like 23 together with a floor surface of ply-wood or the like 24 which is offset with respect to the marginal edges of certain of 15 said side beams 21 to provide a lap joint with adjacent floor sections as indicated at 25 in Fig. 6 of the drawings.

A number of shoe or runner elements 26 are secured substantially end to end upon the surface 20 24 of the floor sections 20 adjacent the peripheral edges thereof and elsewhere to conform to the outline of the floor plan of the building being erected. In the present instance the shoe or runner members 26 may be provided with rounded 25 upper corners or slightly tapered sides to facilitate engagement thereof with the grooves 14 in units or sections 1, said shoes 26 in other respects being of substantially the same cross section dimensions and shape as the grooves 14 in the bottom end of 30 the several types of wall and partition units so that said runner members 26 snugly engage the same in the manner shown in Fig. 6. The several units or sections are arranged in successively 35 abutting relation vertically on the runners 26 so that the projecting tongues 15 of certain sections engage the adjacent vertical groove 13 in the next unit or section, and the sections or units having no projecting tongue or like element are interlocked with adjacent units by means of independent 40 keys or feather elements 18 in the manner previously described, a key or feather being similarly employed to effectively interlock one or the other of the corner units with an adjacent unit or section as shown in Fig. 7 of the drawings. 45

After the several units have been assembled in the foregoing manner to complete the walls and partitions of a one-story building, ceiling units designated generally as 27 are superimposed upon said walls and partitions, and in the present instance said ceiling units 27 comprise end beam members 28 and side beams 29 and 29a respectively, said beams being braced by cross members or struts 30 and arranged for interlocking engagement with the grooves 12 in the 55 top ends of the wall and partition units. In addition the ceiling units 27 are surfaced or panelled at the under side with fibre board, sheet rock or like insulating material 31 which is secured thereto and offset with respect to the side beam members 29a so that each unit will overlap a portion of adjacent sections as indicated at 32 in Fig. 9, cleats 33 being employed to prevent relative vertical displacement thereof.

In the present instance the end beams 28 of 65 the ceiling sections 27 are of slightly greater depth and substantially one-half the width of the grooves 12 in the upper ends of the several wall or partition units so that sufficient clearance or space is provided for reception of said beams 28 as well as beams 34 constituting the outer end frame members of pre-formed roof units designated generally as 35 and comprising in addition side edge beams or the like 36 and 36a and opposite end beam 37. A suitable covering or 70 75

5 roof section 38 is secured to the beams 34, 36, 36a and 37 and these together with said roof 38 are disposed at an inclined angle with respect to said end beam members 34 and 37, said beams 37 being arranged for interlocking engagement with the corresponding end beam 37 of an oppositely inclined roof section 35 at the ridge line in the manner shown in Fig. 6 of the drawings wherein certain of said end beam members 37 are provided with toes 39 arranged to engage the underside of certain of said beam members 37 of the companion sections 35 and eliminate the necessity for the usual continuous ridge pole. As shown, the roof paneling or covering 38 of each section is 10 offset with respect to the edges of the side beams 36a thereof, so as to provide a lap joint between adjacent roof sections. By providing the end beam members 28 of the ceiling sections 27 of substantially one-half the width of the grooves 12 in the upper ends of the several wall and partition units, it will be observed by reference to Fig. 6 of the drawings, that when two end beams of adjacent sections are disposed in abutting relation, the depending portions thereof may be 15 effectively employed to snugly interlock with grooves 12 in the upper ends of several units 1 for erecting interior partitions, the bottom end grooves 14 being engaged by the shoes or runners 26 secured to the upper surface of the flooring 20 panels or sections 24 in the manner previously described and illustrated in Figs. 6 and 8 of the drawings.

On the other hand the side beam members 29 of the ceiling sections 27 which reside in the outer 35 walls of a building are preferably of substantially the same width as the grooves 12 and 14 in the top and bottom ends of the several wall units and gable units 1c so that said beams snugly interlock with the top and bottom grooves thereof of as shown in Fig. 9 of the drawings, the grooves 12a in the top or upper ends of the gable units 1c being engaged by the outer side beams 36 of the roof units 35, so that said gable units may be 40 interlocked between the ceiling sections 27 and said roof units 35 to effectively close the opening created by the oppositely inclined roof sections or units 35 and ceilings 27.

In lieu of the standard or gable type of roof structural units previously described, the invention 50 may be adapted to the construction of units or sections for erecting a roof of the so-called hipped type, wherein the sections or units are constructed or fabricated in a manner similar to the previously described standard or gable roof sections but differ therefrom in that the former are shaped to the correct degree of bevel and angle cut-off at the interlocking hip line, which is of the same split construction as embodied at the ridge line intersection of the gable type roof units. 55 In either of the foregoing types of roof construction, while the sheathing or paneling 38 shown and described is preferable for roof coverings of sheet metal and other roofing compositions as well as asphalt and slate shingles, in the event 60 that a wood shingle roofing is chosen, it is preferable that spaced slats be substituted for the sheathing or paneling 38 in the initial construction of the several roof units.

The present invention may be employed with 65 equal effectiveness in the erection of buildings having more than one floor level or story and while such a building is erected in substantially the same manner as that previously described, certain differences in structure are obviously 70 necessary. Referring particularly to Fig. 8 of

the drawings, combined ceiling and floor sections designated generally at 41 are provided and include a framework or skeleton composed of side beam members 42 and end beam members 43 and 43a respectively as well as cross members 43b. 5 The top and bottom faces of the combined units or sections 41 are covered by panels or sections of ply-wood or the like 44 and fibre board or other like insulating material 45 respectively. In the present instance, the end beam 43 of said sections which resides in the outer wall structure of the building, is of substantially the same width as the grooves 12 in the upper ends of the several wall and partition units previously described so that the same will snugly interlock therewith, and 10 the opposite end beam members 43a are of substantially one-half the width of said grooves 12 so that both end beams 43a of abutting sections 41 will snugly engage the grooves 12 as shown to effectively interlock with the upper ends of several 15 partition units.

The several wall and partition units for the second or other upper story of the building are interlocked with the combined floor and ceiling sections 41 by means of shoe or runner members 25 46 secured to the upper surface of the floor panels 44 much in the same manner that the lower ends of the wall and partition units of the first floor or story are interlocked with floor sections 20, said runner members 46 conforming to the outline 30 of the floor plan of said upper story and having rounded or beveled upper corner edges or slightly tapered sides to facilitate engagement thereof with the grooves 14 in the lower ends of the several wall and partition units, so as to snugly engage the same in the manner illustrated. After 35 the several wall and partition units of the upper story are erected in the foregoing manner, ceiling and roof units 27 and 35 respectively may be interlocked with the grooves 12 in the upper ends 40 thereof in the manner previously described to complete said building.

In the event that the floor plan of the building calls for the erection of interior partitions at locations therein other than along the line of abutment of adjacent end frame members 28 and 43a of the ceiling units 27 and 41 respectively, shoes or runners 47 may be secured to the sheathing panels 31 and 45 respectively of said units for the purpose of engaging the grooves 12 in the 50 upper end edges of appropriate partition units 1 to secure the latter in the desired position in the manner shown in Fig. 8 of the drawings. Similarly, in instances where the outermost units of the several interior partitions abut units disposed in the exterior walls of a building, the same may be relatively interlocked by securing shoes or runners 48 vertically to the sheathing panels 8 of said exterior wall units for the purpose of 55 engaging the groove 13 in the adjacent side edges 60 of said outermost partition units.

The facings or surface panels of the several wall and partition units as well as the companion floor, ceiling and roof units herein described may be provided with factory punched apertures or 65 holes (not shown) disposed at substantially equally spaced intervals closely adjacent the peripheries of said units for the reception of nails, screws or the like, to secure the component units together in interlocking relation. However, during 70 erection of a building, the several structural units need only be secured or fastened together at strategic points until the building is enclosed against the elements of nature, after which the fastening may be completed. It will be seen from 75

the foregoing description therefore, that the novel construction of the several wall and partition and companion units or sections herein disclosed permits the erection of a building which is extremely rugged and may be firmly assembled in a manner that does not require the services of skilled labor.

The foregoing description has been restricted to the construction and assembly of units or sections which are complete including surface sheathing and panel. However, for the purpose of reducing unit weight and bulk size, it may be desirable in certain instances to furnish said structural units or sections in a knocked down or unassembled state, the component elements of which, however, would be pre-cut to the desired dimensions and pattern and suitably marked for assembly in the field under the present so-called "ready-cut" procedure.

20 As will be observed by referring to the drawings, the cross members or struts 23 and 30 respectively of the floor and ceiling units 20 and 27 are of less height than the end and side beam members thereof and are secured in relatively spaced relation with respect to the surface paneling or sheathing to provide openings for the passage of wiring for electricity as well as pipes for gas, water and the like, and while a preferred embodiment of the invention has been set forth for 25 the purpose of description, it is not intended that the invention be precisely limited thereto but that modifications and changes in the details of construction thereof may be incorporated within the scope of the annexed claims.

35 What I claim is:

1. In a building of the character described, a plurality of wall and partition units having grooves in the top end edges thereof, a ceiling structure comprising a plurality of units each including end and side frame members and sheathing panels, certain of the side and end frame members of said ceiling units being disposed within the grooves in the top end edges of said wall and partition units, and a roof structure comprising a plurality of units each including end and side frame members and sheathing panels, the outer end frame members of oppositely positioned roof units being also disposed within said grooves in the top end edges 40 of the several wall units in at least two opposite exterior walls of the building.

2. In a building of the character described, a plurality of wall and partition units disposed vertically with their side edges in respectively abutting relation and having grooves in the top end edges thereof, means forming a part of certain of said wall and partition units for interlockingly engaging adjacent wall and partition units to secure the same together, means interlockingly engaging portions of other wall and partition units along their adjacent side edges to secure the same together, a ceiling structure comprising a plurality of units each including end and side frame members and sheathing panels, certain of the side and end frame members of said ceiling units being disposed within the grooves in the top end edges of the wall and partition units, and a roof structure comprising a plurality of units each including end and side frame members and sheathing panels, the outer end frame members of oppositely positioned roof units being also disposed within the grooves in the top end edges of the several wall units in at least two opposite exterior walls of the building.

75 3. In a building of the character described, a

plurality of wall and partition units having grooves in the top end edges thereof, a ceiling structure comprising a plurality of units each including end and side frame members and sheathing panels, certain of the side and end frame members of said ceiling units being disposed within the grooves in the top end edges of said wall and partition units, a roof structure comprising a plurality of units each including end and side frame members and sheathing panels, the outer end frame members of oppositely positioned roof units being also disposed within said grooves in the top end edges of the several wall units in at least two opposite exterior walls of the building, and other wall units having grooves in the top and bottom end edges thereof disposed intermediate said ceiling and roof structures in opposite exterior walls of the building with the outermost side frame members of the extreme ceiling and roof units disposed within said grooves in the bottom and top end edges respectively of said last-mentioned other wall units.

4. In a building of the character described, a floor structure, a plurality of wall and partition units disposed vertically on said floor structure and having grooves in the top and bottom end edges thereof, means on the surface of the floor structure disposed within the grooves in the bottom end edges of said wall and partition units to secure the same in predetermined positions on said floor structure, a ceiling structure comprising a plurality of units each including end and side frame members and sheathing panels, certain of the side and end frame members of said ceiling units being disposed within the grooves in the top end edges of the wall and partition units, and a roof structure comprising a plurality of units each including end and side frame members and sheathing panels, the outer end frame members of oppositely disposed roof units being also disposed within the grooves in the top end edges of the several wall units in at least two opposite exterior walls of the building.

5. In a building of the character described, a floor structure, a plurality of wall and partition units disposed vertically on said floor structure and having grooves in the top and bottom end edges thereof, means on the surface of the floor structure disposed within the grooves in the bottom end edges of said wall and partition units to secure the same in predetermined positions on said floor structure, a ceiling structure comprising a plurality of units each including end and side frame members and sheathing panels, certain of the side and end frame members of said ceiling units being disposed within the grooves in the top end edges of the wall and partition units, a roof structure comprising a plurality of units each including end and side frame members and sheathing panels, the outer end frame members of oppositely disposed roof units being also disposed within the grooves in the top end edges of the several wall units in at least two opposite exterior walls of the building, and other wall units having inter-engaging portions and grooves in the top and bottom end edges thereof disposed intermediate said ceiling and roof structures in opposite exterior walls of the building with the outermost side frame members of the extreme ceiling and roof units disposed within the said grooves in the bottom and top end edges respectively of said last-mentioned other wall units.

6. In a building of the character described, a floor structure, a plurality of wall and partition units disposed vertically on said floor structure

with their side edges in respectively abutting relation and having grooves in the top and bottom end edges thereof, means on the surface of the floor structure disposed within the grooves in the bottom end edges of said wall and partition units to secure the same in predetermined positions on said floor structure, means forming a part of certain of said wall and partition units for interlockingly engaging adjacent wall and partition units to secure the same together, means inter-engaging portions of other wall and partition units along their adjacent side edges to secure the same together, a ceiling structure comprising a plurality of units each including end and side frame members and sheathing panels, certain of the side and end frame members of said ceiling units being disposed within the grooves in the top end edges of the wall and partition units, and a roof structure comprising a plurality of units each including end and side frame members and sheathing panels, the outer end frame members of oppositely positioned roof units being also disposed within the grooves in

the top end edges of the several wall units in at least two opposite exterior walls of the building with the inner adjacent end frame members thereof interlocked with each other.

7. In a building of the character described, a plurality of wall and partition units having grooves at least in the top end edges thereof, a roof structure comprising a plurality of units each including end and side frame members and sheathing panels, the outer end frame members of oppositely positioned roof units being disposed within the top end edges of the side and end frame members in at least two opposite exterior walls of the building, and a ceiling structure comprising a plurality of units each including end and side frame members and sheathing panels, certain of the side and end frame members being also disposed within the grooves in the top end edges of said wall and partition units to support the latter against outward displacement due to 20 roof thrust.

KARL F. OTTO.
